CLAIM

The ornamental design for a brush for sport's shoes, as shown and described.

DESCRIPTION

FIG. 1 is a perspective view of a brush for sport's shoes according to the invention;

FIG. 2 is a left side view of a brush for sport's shoes according to the invention, the right side view being a mirror image thereof;

FIG. 3 is a top view of a brush for sport's shoes according to the invention;

FIG. 4 is a bottom view of a brush for sport's shoes according to the invention;

FIG. 5 is a front end view of a brush for sport's shoes according to the invention; and,

FIG. 6 is a rear end view of a brush for sport's shoes according to the invention.

The broken lines are for illustrative purposes only and form no part of the claimed design.
